UNITED STATES PATENT OFFICE.

WILLIAM MILTON BROWN, OF JOHNSTOWN, PENNSYLVANIA, ASSIGNOR TO THE LORAIN STEEL COMPANY, A CORPORATION OF PENNSYLVANIA.

UNIVERSAL SWITCH-BOX.

No. 901,776.

Specification of Letters Patent. Patented Oct. 20, 1908.

Application filed December 2, 1907. Serial No. 404,842.

To all whom it may concern:

Be it known that I, WILLIAM MILTON BROWN, of Johnstown, in the county of Cambria and State of Pennsylvania, have 5 invented a new and useful Improvement in Universal Switch-Boxes, of which the following is a full, clear, and exact description, reference being had to the accompanying drawings, which form a part of this specification.

10 My invention has relation to spring boxes for switches, and especially to that class of switches known as derailing switches or crossing protectors, in which the conductor is required to cross the tracks which are crossed by the tracks on which his car is running, and if the road is clear, he manually closes the tongue of the derailing switch, and signals the motorman to cross.

15 20 Prior to my invention, it was necessary to make a different box for each switch as the conditions of each switch differ, due to different rail sections, different angle of the crossing, and location of the switch lever.

25 30 The object of my invention is to provide a box which will be of a universal character, or adjustable, to meet the requirements for different rail sections, different angles of crossing and location of switch levers.

35 35 With these objects in view, my invention consists in a switch box of sufficient height for the highest rail section, together with a chock or filler member adapted to be interposed between the box and the switch structure, the one side of the chock interlocking with the grooves or ribs on the box, and the other side of the chock conforming with the rail section of the switch. Mounted within the box, are two shafts connected together by

40 45 40 means of spur gears; one of the shafts is connected to the switch tongue, and the other is connected by means of a rod, to the switch lever.

45 My invention also consists in the novel construction, arrangement, and combination of parts pointed out in the appended claims, and illustrated in the accompanying drawings, in which:

50 50 Figure 1, is a plan view of my improved box with the cover removed, and showing a portion of a tongue switch to which the box is attached; Fig. 2, is a side elevation of the same. Figs. 3 and 4 are sectional views on the lines III—III and IV—IV of Fig. 1 re-

spectively; Figs. 5 and 6 are sectional views 55 on the lines V—V and VI—VI of Fig. 4 respectively.

A is the switch box, B the switch structure, and C is a chock which is interposed between the box and the switch structure, the three members being secured together by the screws c, c. The inner face of the chock is provided with grooves c', c', which interlock with projections a, a, on the box proper, and the outer face c² of the chock conforms to 65 the shape of the switch structure.

The inner face of the chock is always made to conform to the contiguous surface of the switch box, while the outer face is made to conform to the contour of the face of the 70 switch with which the box is to be used.

Cast integrally with the main box A, and in alinement with each other, are the two lugs a', a'. Projecting downwardly from the main box A, is the tubular projection A', 75 the end of which is flanged as at A². Mounted on the lower end of this tube, and capable of being rotated thereon, is a tubular cap or cover D. This cap is provided with the internal flange d, and the external flange d'. 80 Passing through the flange A², are the hook bolts E. The hook ends of these bolts grasp the flange d' of the cap and clamp it to the bottom of the tubular end of the casing. Projecting from the side of the tubular cap, is 85 the flanged outlet d², to which the pipe connection leading to the switch lever box is made, and centrally located on the bottom of the cap is the step bearing d³. This step bearing is in alinement with a lug a², which 90 is cast integrally with the main box A.

F is the switch tongue, and projecting therefrom, and through an opening in the switch structure, is the lug f, to which is connected the operating rod G by means of the nuts g, g, while the other end of this rod is connected to a crank H. Surrounding the rod G, and adjacent to the crank H, is the bracket J, which is secured to the side of the box A by means of the screws j, j. The 95 100 100 orifice in the bracket J through which the rod G passes is elongated (see Fig. 3) for the purpose hereinafter described.

Surrounding the rod G, and bearing against the inner face of the bracket J, is the flanged collar g', and g² is a flanged nut on the rod G between the collar g' and the switch tongue. This flanged nut is pro-

vided with a jam nut g^3 , and interposed between the collar g' and the flanged nut g^2 is the compression spring g^4 . The function of this spring is to normally hold the switch 5 tongue in the position shown, namely: the open position, so as to derail a car before the crossing is reached.

Passing through lugs a' , a' , is the pin K , and surrounding this pin is the sleeve H' , to the upper end of which the crank H is connected, and interposed between the sleeve and the lug a' is a series of washers k , k , k . The lower end of this sleeve is provided 10 with a clutch member H^2 . Surrounding this pin K , and below the sleeve H' , is the sleeve L , the upper end of which is provided with a clutch member L' , and the lower end is provided with a toothed sector L^2 .

Passing through the lug a^2 , and into the 20 step bearing d^3 is the pin M , and surrounding this pin is the bushing N , the upper end of which is provided with the toothed pinion N' , and the lower end with the crank N^2 , to which is connected one end of an operating link N^3 . This operating link passes from the switch box through the flanged opening d^2 and the pipes connected thereto, to the operating lever.

Secured to the outside of the sides of the 30 box A , by the screws p , p , are the angle bars P . The lower face of these bars is on a line with the bottom of the switch structure B , and they are provided to assist in supporting the weight of the switch box on 35 the cross-ties.

Just before the car reaches the derailing switch, the motorman brings the car to a stop, the conductor crosses the tracks of the crossing railway, and if the road is clear, he 40 raises the operating lever, rotating the pinion N' and with it the sector L^2 . The movement of this through the medium of the clutch members L' and H^2 will rock the crank H , draw the rod G and with it the tongue F against the action of the spring g^4 . The car now passes over the closed switch 45 and the crossing, and as soon as the car has passed over the switch, and the conductor releases the operating lever, the switch will be reset for derailing through the action of the spring g^4 . If a car should trail the switch, or pass over the tracks in the reverse direction, it would merely close the switch, compress the spring g^4 , and rotate the sleeve 50 H' , but would not rotate the sleeve L , as the lost motion between the clutch members H^2 and L' , is great enough to take care of this movement. After the car has passed the switch, the spring will again reset the switch.

As previously stated, my improved spring box is designed to take care of various differences of switches caused by different conditions, and is accomplished in the following manner: If the box is to be attached to a 60 switch structure of a lower rail section than

that shown in the drawings, a chock C , whose outer face is adapted to that of the switch structure is supplied, and the angle bars P are placed with their lower faces on a line with the bottom of the switch structure. If the hole in the lug f on the tongue is higher than that illustrated in the drawings, the proper number of washers k , are removed from above the sleeve H' , and placed below the sleeve L , the teeth of the sector L^2 merely sliding up on the teeth of the pinion N' . The teeth on the pinion N' are of sufficient length to allow adjustment from the highest to the lowest point. If the link N^3 does not leave the box at the proper angle to line up with the operating lever, the hook bolts E , are loosened, and the pin M is removed, thereby releasing the sleeve N . The cap or cover D is rotated so as to align the rod N^3 with the operating lever; the sleeve N is replaced, and the pin M inserted into its place and the bolts E are tightened.

I do not wish to limit myself to the detail construction and arrangement of parts as shown and described, as various changes can 90 be made without departing from the spirit and scope of my invention.

Having thus fully described my invention, what I claim as new, and desire to secure by Letters Patent is:

1. In a switch-box, a tongue operating rod, a link leading to an operating lever, connections between the operating rod and the link, and means for changing the angle between the operating rod and the link. 100

2. In a switch-box, a tongue operating rod, a link leading to an operating lever, connections between the operating rod and the link, and means for changing the angle between the operating rod and the link, in 105 combination with a casing having an adjustable portion to compensate for difference in angle between the operating rod and the link.

3. In a switch box of the character described, a casing inclosing the operating mechanism, and a chock interposed between the casing and the switch structure, one of its faces conforming to the face of the switch structure and the other face conforming to 115 the face of the casing, for the purpose specified.

4. In a switch of the character described, a casing inclosing the operating mechanism, an adjustable cap having a pipe socket, and 120 a chock interposed between the casing and the switch structure.

5. In a switch-box, a crank, connections between the crank and the switch, a second crank, an operating link connected thereto, 125 and adjustable operating means between the two cranks.

6. In a switch-box, a crank having a pinion connected thereto, a switch member, connections between the crank and the switch 130

- member, a gear in mesh with the pinion, a crank connected thereto, and an operating link connected to the last mentioned crank.
7. A switch box having a crank, a switch member connected to the crank, a pinion, a clutch connection between the pinion and the crank, a sector in mesh with the pinion, a crank connected thereto, and an operating link connected to the crank.
10. 8. A switch - box having a crank - shaft journaled therein, a switch member connected to the crank shaft, a pinion in line with and connected to the crank-shaft by clutch members, a sector in mesh with the pinion, a second crank shaft journaled in the switch-box and connected to the sector, and an operating link connected to the second crank shaft.
9. In a switch operating mechanism, a spring box of standard form, and means for attaching the same to switch structures of varying form, consisting of an interposed filler or attaching member having one side adapted to the standard box, and the other side adapted to the particular switch structure to which the box is attached. 20
- In testimony whereof, I have affixed my signature in presence of two witnesses.
